UNITED STATES PATENT OFFICE.

ALBERT WHITE, OF LOWELL, MASSACHUSETTS, ASSIGNOR TO CHARLES E. HOUSE, OF MANCHESTER, FRANK E. HOLMES, OF ROCKY HILL, AND MILTON S. TRACY, OF GLASTONBURY, CONNECTICUT.

VICE.

SPECIFICATION forming part of Letters Patent No. 557,090, dated March 24, 1896.

Application filed September 29, 1893. Renewed November 11, 1895. Serial No. 568,639. (No model.)

To all whom it may concern:

Be it known that I, ALBERT WHITE, a citizen of the United States, residing at Lowell, in the county of Middlesex and Commonwealth of Massachusetts, have invented a certain new and useful Improvement in Vises, of which the following is a specification.

My invention relates to vises; and it consists in the combinations and devices herein-
10 after described and claimed.

Usually vises of the kind most nearly resembling the one herein shown and described are provided with a rack cast in one piece with or otherwise attached to the stationary 15 or rear jaw and with a single dog, carried by the sliding or front jaw and adapted, by a partial revolution of a screw-rod or cam-rod, to be allowed or forced to engage said rack, the further rotation of said rod tending to 20 advance the dog relatively to the sliding jaw, but owing to the resistance of said rack giving an actual backward movement to the sliding jaw. In such vises the sliding jaw is moved by hand to adjust the distance between the jaws, according to the thickness of 25 the work to be grasped, and the work is then firmly clamped by turning a lever or handle secured on the actuating-rod or screw-rod. The expense of cutting such racks is consider- 30 able and the racks, if cast, are so coarse as to prevent a fine adjustment of the distance between the jaws, according to the thickness of the work, without frequently leaving the dog in such a position as to require a consider- 35 able movement of the actuating-rod to bring the dog into engagement with the tooth of the rack next in advance of said dog. This is a disadvantage, because the engagement of the dog and the clamping of the work are both 40 successively accomplished in less than a complete revolution of the actuating-rod or its handle, so that the less the angular movement of the handle necessary to cause the engagement of the dog the more firmly the work can 45 be clamped by the further angular movement of said handle. The teeth of the rack, whether cast or cut, if made too fine will not be strong enough to stand the strain and will be broken by the pressure of the dog, and the tooth or 50 engaging end of the dog, if made fine enough

to engage a very fine rack, will for the same reason be easily broken. To avoid these defects I make a very coarse rack, which, being coarse, may be cast on the upper jaw and needs no finishing and is therefore inexpensive, and I use on the sliding jaw a plurality of dogs, so arranged that the distance between the teeth or engaging ends of said dogs is not an exact multiple of the pitch or distance between two successive teeth of said rack. Evidently more than two such dogs may be used; but in any case, when the distance between the teeth of two such adjacent dogs is divided by the pitch of the rack, the remainder will be a fraction, which, reduced to its lowest terms, will have one for a numerator and a denominator equal to the number of dogs used—that is, if two dogs are used, when one dog is against the rear face of a tooth of the rack the tooth of the other dog will be half-way between two teeth of said rack, and when three dogs are used and one of them is in working position the other two dogs will be respectively one-third and two-thirds of the pitch distance of the rack from the rack-teeth next in front of said last-named dogs, respectively—that is, as near as practicable—taking into account the method of manufacture and the accuracy attainable consistently with the low price at which the vises must be sold.

I provide means whereby the dogs may be independently moved by a yielding pressure into engagement with the rack, so that when the tooth of one of the dogs strikes upon the end of a tooth of the rack the other dog or dogs will not thereby be held out of such engagement.

Usually the downward thrust of the dog is sustained by the actuating-rod and has a tendency to bend said rod and to make the turning of said rod more difficult; but I support the dog or dogs (this part of my invention being applicable to a vise having one or more dogs) upon a slide which sustains this downward thrust and may be placed very near said rod, leaving to said rod merely the task of moving the slide in a path parallel with said rod.

For convenience of finishing the cam-surface of the cam-piece, said cam-piece is first

made and then placed loosely upon the actuating-rod, and upon said rod is subsequently immovably cast a hub provided with a tongue to enter a slot formed in the rear of said cam-piece to cause the cam to rotate with said rod. The cam is preferably loose enough on its actuating-rod to allow the working surface of the cam and the contiguous surface of the dog-carrying slide better to accommodate themselves to each other and to work with less friction. The actuating-rod is retained in a half-journal box or notch in the sliding jaw by ears cast on said sliding jaw and holding the dog-carrying slide above said rod.

15 In this vise two slides are used, one of which carries the dogs, as above intimated, and the other of which carries cushions or yielding springs which move the dogs into engagement with the rack, and other springs are used to restore these slides to position when the handle of the actuating-rod is returned to its starting-point. The sliding jaw has means of holding an extension-jaw which projects above the bench to hold work against 25 pins in the bench.

In the accompanying drawings, Figure 1 is a plan of a vise containing my improvement attached to a bench, a part of the bench and of the attaching-plate being broken away to 30 show the construction of the slide of the front jaw and of the parts supported thereby; Fig. 2, a side elevation of said vise and bench, partly in section, on the line 2 2 in Fig. 1; Fig. 3, a plan of the rear portion of the sliding jaw and parts supported thereby; Fig. 4, a vertical cross-section on the line 4 4 in Fig. 6 of the vise and bench; Fig. 5, a plan of the dog-carrying slide; Fig. 6, a vertical section of the rear portion of the rack and sliding jaw and 40 a left-side elevation of the rear portion of the actuating-rod, the cam, the dogs and springs, and their slides; Fig. 7, a left-side elevation of the rear hub of the actuating-rod and the cam; Fig. 8, a vertical section on the line 8 8 in Fig. 9; Fig. 9, a plan of the front portion of 45 the sliding jaw, actuating-rod, and extension-jaw.

The stationary or rear jaw A has a backwardly-extending attaching-plate *a* to enable 50 the vise to be attached by screws or bolts *b* to the bench B in the usual manner. To the under side of the attaching-plate *a* is secured a rack *a'*, preferably cast in one piece with said plate and with the jaw A, and of the 55 usual construction, except that it is preferably much coarser or of greater pitch than is customary.

The attaching-plate *a* is provided with grooved ways *a*³ to receive the side edges of 60 the slide *c* of the front or sliding jaw C, said slide *c* being of the general shape of a trough and being provided in the bottom with a longitudinal slot for the escape of chips and dust, all in a well-known manner.

65 The actuating-rod D is preferably of wrought-iron or steel and is provided with a handle *d'* preferably cast thereon and with a

rear hub *d*, also preferably cast on said rod D and provided with an annular groove, the bottom of which forms the rear journal *d*² of said rod and turns in a notch *c*⁴ in the vertical rear end *c*⁵ of the slide *c*. This construction of the cam-rod is similar to what is shown in United States Letters Patent No. 469,493, granted February 23, 1892, to me, except that 70 in that patent said annular groove is formed directly in the actuating-rod. The front journal of the rod D may turn in a journal-box E, which fills an opening *c*² in the front jaw C, as described in said patent, or the piece E 75 may be a hub rigidly attached to said rod. In either case the opening *c*² must be of sufficient size to admit the rear hub *d*.

The cam *d*⁵, instead of being cast rigidly on the rod D, is made and its cam-surface finished and said cam is placed loosely on said rod before said rod is placed in the sand for casting the handle *d'* and hub *d*. The hub *d* is provided with a tongue or projection *d*⁶, which enters a notch *d*⁶ in the cam *d*⁵, causing said cam to be rotated by the rotation of the rod D. The spiral cam-surface *d*⁷ is on the front end of the cam *d*⁵ and has a greater pitch at the rear part or beginning of said spiral at *d*⁸.

95 A dog-carrying slide F is supported on horizontal ways *c*⁶, which are formed on the inside of the slide *c* and its rear end is forced back against the cam *d*⁵ by a spring *f* (represented as a spiral wire spring) compressed between the front end of said slide F and an inward projection, (represented as a transverse tie *c*⁷), which may also form an intermediate bearing for the actuating-rod D, said spring being prevented from displacement on the slide F 105 by a stud *f'*, which projects from the front of said slide F and enters the end of said spring.

The dogs G G' are bent levers, the rear vertical arms *g* *g'* of which extend down through transverse slots *f*² *f*³ in said slide F and are 110 loose in said slots and may be turned slightly on the front edges of said slots in the vertical plane in which the rod D lies to raise the teeth or front ends *g*² *g*³ of said dogs into engagement with the rack *a'*. The front horizontal arms *g*⁴ *g*⁵ of the dogs G G' may be 115 guided when falling away from the rack by the sides of the depressions *f*⁴ *f*⁵ in the top of the slide F, said dogs loosely fitting said depressions.

120 Below the slide F is arranged the spring-carrying slide II, which moves on horizontal ways *c*⁸, like the ways *c*⁶ above described, and is provided in the front part of its upper surface with a groove *h*, holding a spiral spring 125 I weaker than the spring F, the spring I being compressed between the rear end of said groove *h* and a vertical stud *f*⁶, which extends down from the under side of the slide F, the elasticity of said spring I forcing the rear end 130 of the slide II backward against the cam *d*⁵. The spring I for convenience is arranged near one side of the slide II, and to avoid the necessity of accurate fitting and to prevent said

slide H from being turned in such a manner as to stick in the ways c^8 the rear end of said slide H, at the same side with said spring I, may be provided with a backwardly-extending guide projection h' , which bears against the side of the cam d^8 . The slide H carries as many springs or yielding cushions as there are dogs G G', these springs being represented as wire springs J J', each formed of a single wire, one end of which enters a hole h^2 or h^3 in the slide H, the intermediate portion j or j' of each wire being coiled around an upwardly-projecting stud h^4 or h^5 , cast on or otherwise rigidly secured to the top of said slide H near 15 one side of the same, and the other end portion of said wire extending nearly across said slide H and forming a finger j^2 or j^3 , which presses against the back of an upwardly-projecting stop h^6 or h^7 , which limits the forward 20 movement of said finger. When the lever or handle d' is in the proper position (preferably a vertical position) to allow the sliding jaw to be moved by hand, the dogs are out of engagement with the rack and the lower rear arms 25 of the dogs are in front of the fingers j^2 j^3 , but out of contact with said fingers or only in contact with them without pressure, and the rear end of the slide H is in contact with that part d^8 of the cam-surface which has the greater 30 pitch. At the same time the slide F is against the part of the cam having the less pitch. Now by turning the handle d' both of the slides F and H are advanced, the slide H, owing to the greater pitch of the part d^8 of 35 the cam-surface, at first more rapidly than the slide F, pressing the fingers j^2 j^3 against the rear arms of the dogs and raising the front ends of said dogs against the rack a' , as shown in Fig. 6, the teeth of one of said dogs entering 40 an interdental space of said rack and the other of said dogs striking a tooth of said rack and crowding back the corresponding spring-finger or cushion. When a revolution of the cam is completed, the slides are restored 45 to position by the springs f I, the return or straight part d^9 which connects the ends of the spiral cam-surface permitting this, and by striking against the under side of the slide H preventing said cam from being turned in 50 the wrong direction from its initial position. The studs h^4 h^5 and stops h^6 h^7 reach upward far enough to prevent the slide H from rising off from the ways c^8 when the slide F is in position, and said slide F is prevented from rising off from the ways c^8 by ears c^9 , which are cast or otherwise secured on the inner faces of the walls of the slide or trough c and project over said slide F, as shown in Figs. 1, 3 55 and 4, so that there is no danger of the slides F and H or the parts attached to or supported by them being dropped out of the sliding jaw, even when the latter is removed from the fixed jaw. If it becomes necessary to remove any of these parts, the spring f may be lifted 60 out of place by its front end and the slide F may then be pushed forward until it clears the ears c^9 and be raised out of the slide c,

thus releasing the slide H, which may then be removed in a similar manner.

The slide F is arranged so near to the actuating-rod D that said rod cannot be raised sufficiently to disengage the rear journal d' from the notch c^4 , above described, without first removing said slide F.

The removable extension or supplementary jaw K (see Figs. 8 and 9) takes the place of the block of wood commonly used to hold a wide board or similar work against vertical stop-pins inserted in holes in the bench, the tops of the jaws A being usually flush with the top of said bench. Said jaw K is a bar or plate provided in one or both ends with slots k k' to receive loosely the actuating-rod D and having a vertical length sufficient to enable said jaw K to reach above the top of the sliding jaw C and to serve as an upward extension thereof, the distance to which the jaw K extends above the jaw C depending on the length of the slot k or k' placed over the rod D, these slots being of different lengths. The extension-jaw K is held in a vertical position when in use by said rod D and by vertical ribs c^{10} c^{11} , cast on the inside of the slide c, and when not in use may be laid in the trough of said slide c, said ribs c^{10} c^{11} forming, with the rear face of the sliding jaw proper, C, and the sides of said trough, a recess through which said rod D passes.

I claim as my invention—

1. The combination of a fixed jaw, provided with a rack, a movable jaw provided with ways, a slide, supported on said ways, one or more dogs, supported on said slide and adapted to engage said rack, an actuating-rod, journaled in said movable jaw, and a cam, carried by said rod and adapted to move said slide, as and for the purpose specified.

2. The combination of a fixed jaw, provided with a rack, a movable jaw, a slide, supported on said movable jaw, two dogs, fulcrumed on said slide and arranged separately to engage said rack, another slide, supported on said movable jaw, springs or cushions, carried by said last-named slide and caused by the forward movement of said last-named slide to press said dogs against said rack, an actuating-rod, journaled in said movable jaw, and a cam, carried by said actuating-rod and adapted to move both of said slides, as and for the purpose specified.

3. The combination of a fixed jaw, provided with a rack, a movable jaw, a slide, supported on said movable jaw, two dogs, fulcrumed on said slide and arranged separately to engage said rack, another slide, supported on said movable jaw, springs or cushions, carried by said last-named slide and caused by the forward movement of said last-named slide to press said dogs against said rack, a spring, arranged to throw said dog-carrying slide backward with reference to said fixed jaw, and another spring arranged to throw said cushion-carrying slide backward with reference to said dog-carrying slide, an actuating-

rod journaled in said movable jaw, and a cam, carried by said actuating-rod and adapted to move both of said slides, as and for the purpose specified.

5. The combination of a fixed jaw, adapted to be secured to a work-bench flush with the top thereof, a movable jaw, sliding on said fixed jaw and provided with a recess, an actuating-rod, journaled in said movable jaw 10 and passing through said recess, and a supplementary jaw, adapted to enter said recess and to be retained thereby in a vertical position and to extend above said fixed jaw and work-bench, said supplementary jaw being 15 provided with slots of different lengths each of said slots being adapted to receive said actuating-rod and by the length of such slot to determine the distance to which said supplementary jaw extends above said fixed jaw, as 20 and for the purpose specified.

5. The combination of the movable jaw, provided with inwardly-projecting ears, the actuating-rod having a front journal which turns in a hole in said jaw and having a rear 25 journal consisting of an annular groove which turns in a notch in said jaw, the cam fast on said rod, the cushion-carrying slide, movable on said jaw above said rod, the dog-carrying slide, movable on said jaw above said cushion- 30 carrying slide and below said ears and having a downward projection which limits the forward movement of said cushion-carrying slide

and a spring, arranged to force said dog-carrying slide backward against said cam and to prevent the lifting of said slides and said 35 actuating-rod, as and for the purpose specified.

6. The combination of a fixed jaw, provided with a rack, a movable jaw, a slide, supported on said movable jaw, two dogs, fulcrumed on 40 said slide and arranged separately to engage said rack, another slide, supported on said movable jaw, springs or cushions, carried by said last-named slide and caused by the forward movement of said last-named slide to 45 press said dogs against said rack, an actuating-rod, journaled in said movable jaw, and a cam, carried by said actuating-rod and having a cam-surface arranged in contact with the rear ends of both of said slides, that portion of said cam-surface in contact with said 50 spring-carrying slide, when said dogs are out of such engagement, having a greater pitch than the remaining portion thereof to move said dogs quickly against said rack, when 55 said cam is turned, as and for the purpose specified.

In witness whereof I have signed this specification, in the presence of two attesting witnesses, this 26th day of September, A. D. 1893. 60

ALBERT WHITE.
